MATTRESS SUPPORTING STRUCTURE

Franklin O. Church, Buffalo, N. Y., assignor to
Dunlop Tire and Rubber Corporation, Buffalo,
N. Y., a corporation of New York

Application November 9, 1939, Serial No. 303,559

8 Claims. (Cl. 5-239)

My invention relates to a support for mattresses or similar resilient upholstery.

Heretofore, mattresses have been generally supported on steel springs, the most favored construction of which was made of a number of coil springs supported on a base and held in properly spaced relation throughout the area to be supported, and the entire construction enclosed in a cover of ticking. Such a construction was complicated, cumbersome and had a number of mechanical disadvantages.

My present invention provides a mattress supporting structure of simple, light construction that provides a very flexible support for the mattress.

In the supporting structure of my invention, I provide a number of yieldable spaced slats extending lengthwise of the mattress to be supported and supported at suitable intervals as, for example, at each end, or at some positions intermediate the ends, individually on resilient supporting blocks. Each slat is free to bend under the weight supported on the mattress and the resilient block immediately beneath the slat may also yield under the weight without depressing the adjacent slats or those outside of the area of support of the weight.

The slats are held in suitably spaced positions by a resilient or stretchable spacing strip or strips which, however, permit each slat to yield substantially independently of the adjacent slats. The slats are sufficiently yieldable to bend or sag slightly from head to foot, but the slats are made sufficiently stiff so that this deflection is less than the head to foot sag of the conventional spring constructions. The amount of bend or sag in the slats may be controlled by selection of material and shape and dimensions to give the required stiffness. The resilient blocks supporting the slats are compressed under a load providing a yielding platform for the mattress and giving a feeling of depth and comfort.

The weight applied to one side of a bed of this construction, therefore, has no effect on an area occupied by another load and sag in a continuous curve from side to side is eliminated. By making the outside slat at each side of the bed somewhat stiffer, firm side edges are provided. The supporting construction may be covered with a suitable cover. Owing to its simplicity of construction it is light, may be easily stored, shipped and handled, and is free from dust forming materials and is easily cleaned.

Various features of the invention are illus-

trated by way of example in the accompanying drawings in which—

Fig. 1 is a plan view of a mattress and supporting structure embodying my invention, portions of the mattress and of the cover of the supporting structure being removed to show the construction.

Fig. 2 is a vertical section of the mattress support and a part section of the mattress taken on line 2-2 of Fig. 1.

Fig. 3 is a vertical section of the mattress support taken on line 3-3 of Fig. 1.

Fig. 4 is a perspective of a portion of one end of the supporting structure, portions of the cover being broken away.

Figs. 5 and 6 are vertical cross-sections through a modified embodiment of the invention taken midway and through an end respectively of the structure.

Fig. 7 is a detail end view partly in section of a supporting structure made in two parts hinged together.

Fig. 8 is an end view on a smaller scale of a hinged construction in flat or extended position, and Fig. 9 is a similar view of the mattress support in folded position.

Fig. 10 is a vertical cross-section through an embodiment of the invention in which the structure is made in two assembled halves.

Fig. 11 is a perspective view showing these halves nested together for compactness in handling or shipping.

Fig. 12 is a foreshortened vertical section of one-half of the mattress support of Fig. 11.

Fig. 13 is a diagrammatic cross-section showing the position assumed by the mattress and its support under different weights.

Fig. 14 is a vertical section similar to that of Fig. 10 of a section of a modified form of the invention.

Referring more particularly to Figs. 1 to 4 of the accompanying drawings, the invention is illustrated in connection with a bed frame 20 having a number of supporting brackets 21 at its ends and having a cellular or foamed latex mattress 22. The structure for supporting the mattress comprises supporting rails 23 and 24, one at each end, supported on the brackets 21 and which may form a part of the bed frame.

Supported on the rails 23 and 24 respectively are resilient blocks 25 and 26 in which are imbedded the ends of a series of spaced slats 27 extending between the resilient blocks. The blocks 25 and 26 may be of any suitable construction.

In the specific modification shown in Figs. 1

to 4 inclusive, they are made up of molded blocks of cellular rubber or foamed latex rubber suitably recessed to receive the ends of the slats 27 and having these ends cemented in the rubber. The slats 27 are thus held in spaced relation throughout the width of the mattress and are further held in spaced relation by transverse strips 28 which may be secured to the slats in any suitable manner as, for example, by tacks or nails 29, Fig. 4.

The outer or extreme side slats 30 and 31, Figs. 2 and 4, are edged by a strip 32 of resilient material, such as foamed or cellular rubber, thereby avoiding a hard surface. The outer face or edge of this strip may be thus positioned in vertical alignment with the longitudinal rails 33 in a manner similar to the positioning of a box spring of the construction heretofore used. The entire supporting structure may be inclosed in a cover 34 of ticking or other suitable fabric which may be made to cover the upper surface of the slat assembly and all surfaces of the resilient blocks 25 and 26.

It will be apparent from the above that each of the slats 27 may be depressed independently of the others and that the pressure on each slat will be supported principally by the part of the resilient block immediately beneath it. The entire construction, however, forms a unitary structure which may be readily lifted and is particularly light because it consists of the slats which may be made of wood or light metal, and of the resilient blocks which are relatively light because of their porosity and also because they extend only throughout a limited supporting area of the structure.

In the modification shown in Figs. 5 and 6, the arrangement of slats and of the resilient supports or bolsters is similar to that of Figs. 1 to 4, but there is also provided a rail 35 embedded in the resilient supports 25 and 26, as indicated in Fig. 6, and extending above and resting on the side rail 33 of the bed frame.

The cover 34 is extended downwardly as at 36 from the resilient strip 32 and about the rail 35 so as to form a smooth vertical wall or surface in alignment with the outer face of the bed frame rail 33.

In the construction shown in Figs. 7, 8 and 9, the supporting structure is divided on a median line into two parts by making the supporting blocks or bolsters 25 and 26 in two sections 37 and 38 and by bringing the covering material 39 upwardly between the blocks as at 39 and thus to form a hinge construction with the top layer of the covering material. The structure may, therefore, be spread flat as shown in Fig. 8 when in use, or may be folded over as shown in Fig. 9 for storage or transportation.

In the modification shown in Fig. 10 the supporting structure is made in two halves 40 and 41 which are in mirror relation to each other and otherwise are similar to the construction shown in Fig. 5. This permits the two halves to be assembled as shown in Fig. 10 when in use, or to be placed in inverted relation to each other and nested as in Fig. 11 for transportation and storage.

Fig. 12 shows the construction of Figs. 10 and 11 on a larger scale. As shown in this figure, the innermost slats, or those abutting when the two halves are assembled, are provided with rubber cushions or strips 42 to enable the adjacent

slating and having the surfaces of the slats in direct contact.

Fig. 13 illustrates the flexibility of the mattress construction of any of the above modifications. As shown therein if one half, for example the left half of the mattress, be weighted more heavily than the right half, as indicated by the weights 43 and 44, the slats yield to a greater extent under the heavier weight 43 by merely depressing their supporting resilient bolster to a greater extent 10 and without exerting any depressing effect on that part of the support which is occupied by the lighter weight 44.

In the modification shown in Fig. 14 the resilient bolster 54 is provided with recesses 55 15 positioned below the spaces between the slats 27 to lighten the construction and control the resiliency or yielding of the bolster support. By the use of such recesses or by varying the thickness of the bolster or the stiffness of the compositions 20 or springs forming the supports for the slats, the load supporting capacities of the end and intermediate supporting units may be proportioned to the normal load distribution of the load on the bed.

In the modification shown in Fig. 14 the slats are so arranged for a double mattress that one of the slats falls in the center line of the bed and is split into the parts 56 and 57 on separate units. This simplifies the covering of the units 30 with ticking or other material 58. With this construction it is only necessary to turn the end of the ticking over the edges of the slats and tack it in place.

Through the above invention, I have provided 35 a mattress support of a simple, light, convenient and sanitary construction, and one in which an area of the structure may be depressed without causing other areas to sag and which, therefore, provides the effect of great depth and softness. 40

What I claim is:

1. A supporting structure for mattresses which comprises a number of spaced parallel slats and common supporting blocks of molded cellular rubber for said slats, said slats being individually embedded in said blocks. 45

2. A supporting structure for mattresses which comprises a number of spaced parallel slats and common supporting blocks of molded cellular rubber, said slats being imbedded in said blocks. 50

3. A supporting structure for mattresses which comprises a number of spaced parallel yieldable slats and supporting blocks of cellular rubber common to said slats, the outer slats of said structure being stiffer than the inner slats thereof. 55

4. A supporting structure for mattresses which comprises a pair of transverse resilient supporting bolsters, spaced parallel slats extending lengthwise between said bolsters and imbedded therein, a filling rail imbedded in said bolsters and spaced below the outermost slats and a covering extending from said filling rail about and over said slats and over said bolsters. 60

5. A support for mattresses which comprises 65 common transverse bolsters of cellular rubber longitudinally extending spaced slats embedded in said bolsters, said slats being capable of yielding under a weight, said bolsters being recessed in the intervals between said slats.

6. A support for mattresses which comprises 70 a number of spaced parallel slats and transverse resilient supporting bolsters below and supporting said slats, said bolsters being of resilient cellular rubber, said bolsters being common to a number 75

of said slats and said slats being secured to said bolsters.

7. A support for mattresses which comprises spaced transverse bolsters of resilient cellular rubber and spaced longitudinally extending yieldable slats supported on and partly embedded in said bolsters to form a substantially continuous flat supporting surface for a mattress.

8. A support for mattresses which comprises spaced transverse bolsters of resilient cellular rubber and spaced longitudinally extending yieldable slats supported on and partly embedded in said bolsters to form a substantially continuous flat supporting surface for a mattress, and strips extending across and connecting said slats.

FRANKLIN O. CHURCH.
